UNITED STATES PATENT OFFICE

2,424,395

TRANSPORTATION LOAD AND METHOD
OF PREPARING THE SAMEDon F. Hedges, Crown Point, Ind., assignor to
Carnegie-Illinois Steel Corporation, a corpora-
tion of New Jersey

Application October 2, 1944, Serial No. 556,840

14 Claims. (Cl. 105—367)

1

This invention relates to a transportation load and method of preparing the same and is especially adapted for loads of narrow coils of strip metal which stand on end on a railroad car.

In the past, individual coils were banded to prevent uncoiling and then rolled into and lined up crosswise of the car by hand. As each row was completed, the blockers came in measured, cut, fitted, and fastened the timber bracing in place. Each blocker selected the material and blocked according to his judgment and material, this being slow, costly and inefficient. The customer had considerable difficulty in unloading and damage, to both the coils and the car, often resulted when the blocking was ripped out. The coils were blocked solid in the car and thus there were no means for cushioning the impact caused by severe jolting or bumping of the car in transit.

It is an object of my invention to so load the coils that all phases of their handling will be safe.

Another object is to protect the steel by assembling the coils in units which can be conveniently handled with equipment which is available to both loader and customer.

A further object is to protect the steel and equipment by so preparing the load so that it will not shift haphazardly in transit.

A still further object is to prepare the load so that the blocking and lashing can be easily loosened and removed.

These and other objects will be more apparent after referring to the following specification and attached drawings, in which:

Figure 1 is a plan view of one embodiment of the invention showing the coils loaded into a car;

Figure 2 is a vertical section taken on the line II—III of Figure 1;

Figure 3 is a view taken on the line III—III of Figure 1;

Figure 4 is a plan view of an individual unit;

Figure 5 is a sectional view taken on the line V—V of Figure 4;

Figure 6 is a plan view similar to Figure 1 but showing a different embodiment of the invention;

Figure 7 is a vertical section taken on the line VII—VII of Figure 6; and

Figure 8 is a section taken on the line VIII—VIII of Figure 6.

Referring more particularly to the drawings, the reference numeral 2 indicates the narrow coils of strip which are to be loaded into the car. In preparing the load, several of these narrow coils 2 are mounted one on top of the other

2

and strapped to a stool 4 which consists of cross members 6 and skids 8. The coils 2 are fastened together and to the stool 4 by means of straps 9 as shown in Figures 4 and 5. Each individual unit 10 constructed in this manner is of convenient size and weight for handling by crane or truck. In preparing the car for the load, end cleats 12 are spiked to the car floor 14 to limit the longitudinal travel of the load. Guide strips 16 are laid loosely in position along each side of the car and two units 10 are then placed at one end of the car and centered therein with their skids 8 extending longitudinally thereof. The guides 16 are then closed in against the skids 8 at that point and spiked to the car floor 14. These two individual units are then drawn tightly together and fastened by end cross straps 18. Two more units 10 are lined up adjacent the first pair or groups of units with their skids 8 also extending longitudinally of the car and the guides 16 closed in against the skids of the second group of units 10 and spiked in place. The second two units are then drawn tightly to the first two and strapped thereto by short longitudinal straps 20 which extend through the openings 22 in the coils. The second pair of units are strapped together by straps 24. In like manner additional pairs of units are progressively fastened together and to each preceding pair of units throughout the length of the car to form one solid major unit which is free to move a limited amount longitudinally of the car. If desired, the first and last units on each side of the car may be fastened together by means of a longitudinal strap 26 which passes through the openings 22 in the units. After the loading is completed, cleats 28 are wedged between car stakes 30 and guide strips 16 as another factor of safety. With the load assembled in the car in this manner it forms a unit floating load mounted on skids 8 between guide strips 16 which makes it possible for the load to slide longitudinally in the car and dissipate the impact energy from jolting and bumping by means of the friction of the skids on the car floor. The end cleats 12 limit the travel of the load if it should slide too far in either direction. In assembling a load where the units are piled two or more high, the method of loading is practically the same except that the upper layers will be strapped to the bottom layer as shown in Figures 2 and 3. By assembling the load in this manner, the blocking and lashings are standard and the loading and blocking is completed quickly, cheaply and safely without dam-

age to the carrier's equipment or to the coils. In unloading, it is easy to locate the blocking and lashing so that customer can quickly and safely unload the car without damage to the car or to the coils.

In the embodiment shown in Figures 6, 7 and 8, the load is prepared in the same manner as in the embodiment described above, except that each pair or group of units is fastened to the succeeding pair by means of diagonal straps 34 in place of the straps 20 and 24.

While two embodiments of my invention have been shown and described it will be apparent that other adaptations and modifications may be made without departing from the scope of the following claims.

I claim:

1. The method of preparing a transportation load of cylindrical objects having an axial opening therethrough for transit in a railway car or the like which comprises placing two or more objects side by side on end at one end of the car, fastening adjacent objects together by end cross straps passing through the openings in the objects, placing an object against each of the first objects, fastening the second group of objects to the first group by straps passing through the openings in the objects, and progressively fastening additional groups of objects to each preceding group in like manner throughout the length of the car to form one solid major unit.

2. The method of preparing a transportation load of cylindrical objects having an axial opening therethrough for transit in a railway car or the like which comprises forming a plurality of individual units each consisting of several objects placed on skids one on top of the other, placing two units at one end of the car with their skids extending longitudinally of the car, fastening longitudinal guides to the floor against the skids, fastening the two units together by end cross straps passing through the openings in the objects, placing two more units adjacent the first units with their skids extending longitudinally of the car, closing the longitudinal guides against the skids and fastening them to the floor, fastening the second pair of units to the first group, and progressively fastening additional pairs of objects to each preceding pair in like manner throughout the length of the car to form one solid major unit.

3. The method of preparing a transportation load of cylindrical objects having an axial opening therethrough for transit in a railway car or the like which comprises forming a plurality of individual units each consisting of several objects placed on skids one on top of the other, placing two units at one end of the car with their skids extending longitudinally of the car, fastening the two units together by end cross straps passing through the openings in the objects, placing two more units adjacent the first units with their skids extending longitudinally of the car, fastening the second pair of units to the first group by straps passing through the openings in the objects, and progressively fastening additional pairs of objects to each preceding pair in like manner throughout the length of the car to form one solid major unit.

4. The method of preparing a transportation load of cylindrical objects having an axial opening therethrough for transit in a railway car or the like which comprises forming a plurality of individual units each consisting of several objects placed on skids one on top of the other, placing

two units at one end of the car with their skids extending longitudinally of the car, fastening the two units together by end cross straps passing through the openings in the objects, placing two

5 more units adjacent the first units with their skids extending longitudinally of the car, fastening each unit in the first pair to the diagonally opposite unit in the second pair by straps passing through the openings in the objects, and progressively fastening additional pairs of objects to each preceding pair in like manner throughout the length of the car to form one solid major unit.

6. The method of preparing a transportation load of cylindrical objects having an axial opening therethrough for transit in a railway car or the like which comprises forming a plurality of individual units each consisting of several objects placed on skids one on top of the other, placing

20 two units at one end of the car with their skids extending longitudinally of the car, fastening the two units together by end cross straps passing through the openings in the objects, placing two

25 more units adjacent the first units with their skids extending longitudinally of the car, fastening each unit in the first pair to the diagonally opposite unit in the second pair by straps passing through the openings in the objects, progressively fastening additional pairs of objects to each preceding pair in like manner throughout the length of the car to form one solid major unit, and fastening the first and last unit on each side of the car together by a longitudinal strap.

7. The method of preparing a transportation

35 load of cylindrical objects having an axial opening therethrough for transit in a railway car or the like which comprises forming a plurality of individual units each consisting of several objects placed on skids one on top of the other, placing

40 two units at one end of the car with their skids extending longitudinally of the car, fastening the two units together by end cross straps passing through the openings in the objects, placing two

45 more units adjacent the first units with their skids extending longitudinally of the car, fastening each of the second pair of units to the adjacent unit of the first pair by longitudinal straps passing through the openings in the objects, fastening the second pair of units together by cross

50 straps passing through the openings in the objects, and progressively fastening additional pairs of units together and to each preceding pair in like manner throughout the length of the car to form one solid major unit which is free to move a limited amount longitudinally of the car.

7. The method of preparing a transportation load of cylindrical objects having an axial opening therethrough for transit in a railway car or the like which comprises forming a plurality of

60 individual units each consisting of several objects placed on skids one on top of the other, placing two units at one end of the car with their skids extending longitudinally of the car, fastening the two units together by end cross straps

65 passing through the openings in the objects, placing two more units adjacent the first units with their skids extending longitudinally of the car, fastening each of the second pair of units to the adjacent unit of the first pair by longitudinal

70 straps passing through the openings in the objects, fastening the second pair of units together by cross straps passing through the openings in the objects, progressively fastening additional pairs of units together and to each preceding pair in like manner throughout the length of the car

to form one solid major unit which is free to move a limited amount longitudinally of the car, and fastening the first and last unit on each side of the car together by a longitudinal strap.

8. A transportation load of cylindrical objects having an axial opening therethrough and standing on end in a railway car comprising skids for supporting each object, and a longitudinal row of groups of objects arranged side by side with their skids extending longitudinally of the car, each group being fastened to the group adjacent thereto by straps passing through the openings in the objects.

9. A transportation load of cylindrical objects having an axial opening therethrough and standing on end in a railway car comprising a plurality of individual units each consisting of several objects placed on skids one on top of the other, a longitudinal row of groups of units arranged side by side with their skids extending longitudinally of the car, straps passing through the openings in the units in the end groups for fastening them together, and means for fastening each unit in each group to at least one unit in each adjacent group, said means including a strap passing through the openings in one unit of each group.

10. A transportation load of cylindrical objects having an axial opening therethrough and standing on end in a railway car comprising a plurality of individual units each consisting of several objects placed on skids one on top of the other, said skids extending longitudinally of the car said units being arranged in two similar longitudinal rows with each unit being fastened to the adjacent units by straps passing through the openings in adjacent units, and means for fastening the first and last unit in each row together.

11. A transportation load of cylindrical objects having an axial opening therethrough and standing on end in a railway car comprising a longitudinal row of pairs of objects arranged side by side transversely of the car, and means for fastening each pair of objects to the pair adjacent thereto, said means including a strap passing through the openings in adjacent objects.

12. A transportation load of cylindrical objects having an axial opening therethrough and stand-

ing on end in a railway car comprising a longitudinal row of pairs of objects arranged side by side transversely of the car, straps passing through the openings in the objects in each end pair for fastening the objects in each pair together, and means for fastening each object in each pair to at least one object in each adjacent pair, said means including a strap passing through the openings in one unit of each pair.

13. A transportation load of cylindrical objects having an axial opening therethrough and standing on end in a railway car comprising a plurality of individual units each consisting of several objects placed on skids one on top of the other, said skids extending longitudinally of the car, and said units being arranged in two similar longitudinal rows with each unit being fastened to the adjacent units by straps passing through the openings in the adjacent units.

14. A transportation load of cylindrical objects having an axial opening therethrough and standing on end in a railroad car, which load comprises a row of said objects arranged longitudinally in the car, and means for fastening each object to the object adjacent thereto, said means including a strap passing through the openings in adjacent objects.
